UNITED STATES PATENT OFFICE.

ROBERT MIEHLE, OF CHICAGO, ILLINOIS.

PRINTING-PRESS TRIPPING MECHANISM.

1,293,856.

Specification of Letters Patent. Patented Feb. 11, 1919.

Application filed March 8, 1917. Serial No. 153,469.

To all whom it may concern:

Be it known that I, ROBERT MIEHLE, citizen of the United States, residing at Chicago, in the county of Cook and State of Illinois, have invented a certain new and useful Improvement in Printing-Press Tripping Mechanism, of which the following is a full, clear, concise, and exact description.

My invention relates to rotary printing presses and, in one of its embodiments, particularly to that class of rotary presses employing two cylinders, herein disclosed as being members of different printing couples, and tripping mechanism for each of said cylinders, at least one of the cylinders being preferably normally in impression position. I employ a coupler or controlling means for co-operatively relating one of said cylinders (for example a cylinder of a second printing couple) with its tripping mechanism, and mechanism operated by another cylinder (say a cylinder of the first couple) for controlling and positioning the coupler with the tripping mechanism. The mechanism which is employed for positioning the tripping coupler also operates while the cylinder that controls it is in a printing cycle, the said coupler and the tripping mechanism it controls only functioning in the ensuing cycle when the first printing cylinder is out of printing position with its companion printing cylinder.

There are features of my invention which are not to be limited to normally positioning the cylinders of the couples in printing or impression position, another feature of my invention residing in the employment of three or more printing couples, the tripping mechanism of the third printing couple being positioned in the printing cycle ahead of the printing cycle in which the tripping mechanism of the second printing couple is positioned, there being desirably also automatic means whereby the tripping mechanism of the second printing couple is positioned in the printing cycle ahead of the printing cycle in which the tripping mechanism of the first printing couple is positioned. While I prefer to employ tripping mechanism for each of the printing cylinders of the press I do not wish to be limited to this characteristic, but where there is tripping mechanism for each printing cylinder the first cylinder of the series is desirably provided with attendant controlled means whereby the tripping mechanism of the first cylinder may function

and other attendant controlled means whereby the coupler pertaining to the tripping mechanism of the next cylinder is prevented from functioning when the tripping mechanism of the first printing cylinder functions.

In accordance with the invention as I preferably practice it, there are thus a plurality of printing couples and the printing cylinder in each couple is a single revolution cylinder, it being these single revolution cylinders that are preferably normally in impression position.

My invention also has a further object in the conversion of the press into one in which either or both of the printing cylinders of two printing couples may be constituted the printing cylinders in offset printing combinations, each printing cylinder in such a combination having means for bringing it into printing relation with a form cylinder and an impression cylinder and for breaking such printing relation.

Another object of my invention resides in providing a delaying mechanism through which the movements of the first couple into and out of printing position are transmitted to control the tripping mechanism of the second couple, said delaying mechanism functioning to delay the transmission of the movements of said first couple into printing position until after the same has been so moved, whereby the tripping mechanism of the second cylinder is given more time to act without interference from the mechanism which controls it.

While my invention is particularly adapted for rotary printing presses, and is shown for its preferred embodiment, hereinafter described, in connection with a rotary printing press it is not to be limited to that use alone as it will be obvious from the following description that it is well adapted for use on other types of printing presses.

While I have generally outlined prominent features of my invention it is to be understood that my invention is not to be limited thereto and there are other features of my invention to be disclosed.

The invention in all of its aspects will be fully described with reference to the accompanying drawings in which Figure 1 illustrates a printing press embracing my invention adjusted to print twice upon the same side of a sheet, as in two color printing, the cylinders of each printing couple being in

printing relation; Fig. 2 is a view of the press showing many of the parts illustrated in Fig. 1 and other parts not illustrated in Fig. 1, the printing cylinder of the first printing couple being shown in non impression position in full lines and in impression position in dotted lines, the printing cylinder of the second couple being shown in impression position; Fig. 3 is a view generally similar to Fig. 2 with the cylinders of the first printing couple in printing relation and the cylinders of the second printing couple in non-printing relation; Fig. 4 is a view illustrative of tripping mechanism taken on line 4-4 of Fig. 3; and Fig. 5 illustrates a third printing couple and a part of the second printing couple shown in Figs. 1, 2 and 3, Fig. 5 to be read in conjunction with either of Figs. 1, 2 and 3, being together therewith illustrative of a press having three printing couples, it being understood that the third printing couple may be related to a fourth printing couple as the first printing couple is related to the second printing couple.

Like parts are indicated by similar characters of reference throughout the different figures.

The main driving pinion shaft 1 carries a pinion 2 which is in mesh with the main driving spur gear wheel 3 which is fixed with respect to the stub shaft 3¹. This stub shaft is journaled in the frame of the machine to have a fixed axis of rotation whereby the gear wheel 3, that turns with the stub shaft 3¹, has a fixed axis of rotation. The spur gear 3 is in mesh with spur gear 4, fixed upon shaft 15, and gives motion to sheet transfer cylinder 16. The cylinders 17 and 21, in the embodiment of the invention illustrated but to which embodiment the invention is not to be limited, are printing or form carrying cylinders which are normally in printing or impression position, the axes of these cylinders being substantially normally fixed. In the embodiment of the invention illustrated there are two printing couples each including one of the aforesaid cylinders, the cylinder 17 having an impression cylinder 11 as its complement while the cylinder 21 has the impression cylinder 26 as its complement, the sheet transfer cylinder 16 being interposed between the impression cylinders. In a two color press the cylinders 17 and 21 rotate in the same direction on which account these cylinders do not carry gears fixed thereupon that mesh with each other, said cylinders having suitable clearance intervening therebetween at their most adjacent points. Suitable gearing is employed to rotate the cylinders 17 and 21 in their similar directions and to rotate the remaining cylinders in the directions indicated.

I will describe the press of my invention as it is adjusted and arranged to enable it to

be used in performing two printing operations upon the same side of a sheet and in different colors if desired. The axes of printing cylinders (17 and 21 which cylinders rotate in similar directions), the impression cylinders 11 and 26, and the sheet transfer cylinder 16 may be normally fixed but the printing cylinders are tripped into and out of printing position by means of any suitable tripping mechanism provided for each printing cylinder, such as that illustrated. Each printing cylinder is normally dissociated from its tripping mechanism but is coupled therewith by a separate mechanism by the press attendant who has a foot key for the first printing cylinder 17. The tripping mechanism employed may be of the general nature illustrated in my patents 689,505, dated December 24, 1901, and 1,081,420, dated December 16, 1913 with necessary changes.

The foot key A is normally held up by a spring A¹ and is connected by a bell crank A² with a connecting link 57 that is connected with a rocker arm 57¹ that in turn is fixed upon a rod 57², and on which rod there is fixed a cam arm 58 carrying a trip cam portion 58¹. This mechanism constitutes the trip positioning means of the tripping mechanism of the first couple. Whenever the foot key is depressed the rod 57² of the corresponding tripping mechanism is turned to turn the cam arm 58 to move the upper end of the cam arm downwardly to lower the hook 59 into engagement with the tooth e, the parts 59, h¹ of arm k and e¹ constituting elements of a coupler that connects the corresponding printing cylinder with its tripping cam d. The tripping cam d belonging to the first printing cylinder is rotated by the gear e upon which the cam is fixedly located, the gear e in turn being rotated by the pinion f upon the stud g fixed to the frame, the pinion f being in fixed connection with the spur gear wheel h that is in mesh with the pinion 2¹ carried upon the other end of the shaft 1 opposite that which carries the pinion 2 and which latter pinion meshes with gear wheel 3, this shaft passing through the machine from side to side. The tripping mechanisms for both printing cylinders are of similar construction, generally speaking, and similar parts are given similar characters of reference. The gear e of the second printing cylinder tripping mechanism is driven by the intermediate gear e¹ that is driven by the first gear e, the intermediate gear e¹ being mounted to turn upon a fixed stud that is carried by the frame of the machine. The cam groove d¹ in cam d engages a cam roller i upon an arm k loose on shaft l that passes from side to side of the machine and to which shaft the tooth e is fixed. The roller i is mounted upon the stud i¹ upon the inner end of

which the hook 59 is mounted to swing. Shaft l carries two eccentrics l^1 upon each of which a sliding box member l^2 rests, each sliding box member supporting the extension l^3 of the corresponding printing cylinder shaft box l^4 , there being thus one eccentric l^1 in supporting relation to each printing cylinder shaft box l^4 . The arc a b of the cam groove is concentric with respect to the shaft d^2 of the cam. The cam roller i is not bodily moved while engaging this part of the cam groove whereby the arm k is then at rest. The hook 59 carries a cam roller m that may bear upon the operating tripping cam portion 58^1 of the arm 58. The arm k carries stop pin o and hook 59 has a lug p , the elements o and p preventing the hook 59 from separating any farther from the tooth c than illustrated.

Each pair of eccentrics l^1 upon the same shaft l has the position illustrated in Fig. 1 when the printing cylinder corresponding thereto is in its normal operating position, the centers of these eccentrics being normally positioned slightly to the left of the vertical line passing through the centers of the shaft l and the shaft of the corresponding printing cylinder and being between this line and the stationary stop pin Q . As tooth c is in fixed relation to the eccentrics l^1 the stop pin Q holds the shaft l from counter-clockwise rotation to hold the corresponding printing cylinder in working position. The stop pin Q illustrated is upon one side of the press. There may be a similar stop pin on the other side of the press that is to be engaged by an arm fixed upon the other end of the shaft l and positioned similarly to the tooth c to take part in preventing the turning of the shaft l and the eccentrics thereon. When the shaft l is turned clockwise the eccentrics l^1 , being fixed upon the shaft, are also turned clockwise so that the corresponding printing cylinder is lowered to non-printing position. This rotation of the shaft l and the eccentrics l^1 cannot occur until after the part 59^1 of hook 59 is brought into position to enable it to be engaged with the lower side of the tooth c , following the depression of the foot key by the press attendant to lower the arm 58 and the cam part 58^1 thereon to permit the hook 59 to swing downwardly into the hook engaging position. Operative engagement of the part 59^1 of the hook 59 with the tooth c can only occur while the concentric portion a b of the cam groove d^1 is passing by the cam roller i , which is when the line b^1 is passing from the line a^1 to the position of the line b^1 . That is, the tripping may be effected only during the time the leading edge of the printing form travels through the arc a^1 b^1 and during the time the segment a b of the cam slot d^1 is passing by the roller i (see Fig. 3). When the cam roller i is in the portion of the cam groove d^1 between the side a of the arc a b and the shaft d^2 , the cam roller i is drawn toward the shaft d^2 to the position shown at the left of Fig. 3 in connection with the second printing cylinder. The part 59^1 of the hook 59 (assuming that the attendant has pressed down the key A to drop the arm 58 to permit the hook 59 to engage the tooth c) pulls the tooth c in a clockwise direction to permit the corresponding printing cylinder to be lowered by its own weight. When the roller i is in the portion of the cam groove d^1 between the shaft d^2 and the side b of the arc a b the motion of the arm k is reversed whereupon the extension l^1 of the arm k pushes upon the lug c^1 carried by the tooth c to turn the tooth c and the eccentrics l^1 fixed with respect thereto counter clockwise back to the normal position illustrated in connection with cylinder 17, Fig. 3. In coming back to this position the eccentrics l^1 raise the corresponding printing cylinder to working position. It is understood that the roller m (upon the hook 59) supports the hook while this roller m rides over the tripping cam portion 58^1 when the arm 58 that carries this cam 58^1 is in the normal raised position illustrated and while the corresponding printing cylinder is in its normal operating position. The arm 58 may be lowered at any time but should this arm be lowered while the roller i is not in the arcual portion a b of the cam slot d^1 , the swinging end of the hook will ride upon the crown of the tooth c (see Fig. 1) until the roller i is received in the arcual portion a b of the cam-groove d^1 .

The sheets to be printed upon are fed to the first impression cylinder 11 from the feed board not shown. The grippers 32 upon the first impression cylinder 11 take the sheet, numbered 60, from the feed board and carry it around through the line 34 joining the centers of the shafts 10 and 15 (see Fig. 3) to the line 34¹ joining the centers of the shafts 10 and 18 when the first printing operation is initiated, the form 35 upon the first printing cylinder then having printing relation with the sheet 60 upon the cylinder 11. A sheet 61 is shown preceding the sheet 60 being held by the grippers 36 of the transfer cylinder 16 preparatory to transfer to the second impression cylinder 26. The first printing operation upon sheet 60 thus initiated continues during the first revolution of the first impression cylinder 11 and of part of the second revolution thereof (beginning with the time the impression cylinder 11 receives the sheet) until the form 35 upon the first printing cylinder completes its printing upon the sheet 60. During the second revolution of the first impression cylinder 11 the grippers 36 upon sheet transfer cylinder 16 take the sheet 60

is in the portion of the cam groove d^1 between the side a of the arc a b and the shaft d^2 , the cam roller i is drawn toward the shaft d^2 to the position shown at the left of Fig. 3 in connection with the second printing cylinder. The part 59^1 of the hook 59 (assuming that the attendant has pressed down the key A to drop the arm 58 to permit the hook 59 to engage the tooth c) pulls the tooth c in a clockwise direction to permit the corresponding printing cylinder to be lowered by its own weight. When the roller i is in the portion of the cam groove d^1 between the shaft d^2 and the side b of the arc a b the motion of the arm k is reversed whereupon the extension l^1 of the arm k pushes upon the lug c^1 carried by the tooth c to turn the tooth c and the eccentrics l^1 fixed with respect thereto counter clockwise back to the normal position illustrated in connection with cylinder 17, Fig. 3. In coming back to this position the eccentrics l^1 raise the corresponding printing cylinder to working position. It is understood that the roller m (upon the hook 59) supports the hook while this roller m rides over the tripping cam portion 58^1 when the arm 58 that carries this cam 58^1 is in the normal raised position illustrated and while the corresponding printing cylinder is in its normal operating position. The arm 58 may be lowered at any time but should this arm be lowered while the roller i is not in the arcual portion a b of the cam slot d^1 , the swinging end of the hook will ride upon the crown of the tooth c (see Fig. 1) until the roller i is received in the arcual portion a b of the cam-groove d^1 .

being printed upon by the form 35 of the first printing cylinder 17, the grippers 32 releasing the sheet and the grippers 36 taking the sheet when these grippers upon the 5 cylinders 11 and 16 are adjacent to the line 34 during the second revolution of the first impression cylinder 11. During the second revolution of the sheet transfer cylinder 16 from the position shown in Fig. 3 the grippers 40 upon the impression cylinder 26 take the sheet 60, the grippers 36 releasing the sheet and the grippers 40 taking the sheet when these grippers upon these cylinders 16 and 26 are adjacent during said 10 second revolution of the cylinder 16 and are at the line 41 joining the centers of the shafts 15 and 27. When the grippers 40 have sufficiently passed the line 62 that joins the centers of shafts 27 and 22, the second 15 printing operation upon the sheet 60 commences, this second operation being upon the same side of the sheet previously printed upon by the printing cylinder 17 since the sheet transfer cylinder 16 causes the sheet 20 to be taken by impression cylinder 26 with the printed or wet side outside to enable this same wet side to be printed upon by the second printing cylinder 21. The second printing operation initiated upon sheet 60 continues 25 during the first revolution of the second impression cylinder 26 (beginning with the time this cylinder took the sheet) until form 38 upon the second printing cylinder 21 completes the second printing operation 30 upon the same side of the sheet previously printed upon by the first printing cylinder 17. The grippers of the second impression cylinder 26 reach the line 42 and grippers upon a transfer cylinder (not shown) also 35 reach this line adjacent the grippers 40 and take the sheet therefrom during the second printing operation upon the sheet whereafter the sheet is disposed of in any desired 40 way.

45 The press, as illustrated in Figs. 1, 2 and 3, is a multi-couple, multi-cylinder printing press especially adapted for color printing and commonly known as a two color press and by which the same side of a sheet receives two successive impressions by the printing operation of the two printing couples thereupon.

50 Each printing cylinder 17 and 21 is inked by means of form rollers 83 which are distributed in pairs or couples, each couple having a vibrating distributing roller 84 in the usual relation to the form roller. Each distributing roller is driven by suitable gearing, not shown.

55 An arm *r* is fixed at one end upon shaft 57² of the second impression cylinder tripping mechanism, an extension of this arm being normally positioned against a stop *r*¹ by means of the adjustable buffer spring 60 back stop *r*². The cam arm 58 of said second

impression cylinder tripping mechanism is also fixed upon this shaft 57² and moves with the arm *r*. The arm *r* carries a stud *s* upon which the hook lever *s*¹ is mounted to swing, this hook lever being adapted to 70 swing, by its own weight, in a clockwise direction when relieved of restraining influence. The hook *s*², in conjunction with its supporting lever *s*¹, constitutes one member of the coupler or controlling means by which 75 the printing cylinder 21 of the second printing couple is operatively associated with its tripping mechanism. The second member of this coupler is a pin *s*³ engageable by the hook *s*² (Fig. 3) and the lever *s*¹ upon 80 which this pin is mounted, this lever being loosely mounted upon the shaft 57². The lever *s*¹ also carries a cam roller *s*⁵ which is operated upon by a timing cam *s*⁶. A suitable push spring structure *s*⁷ maintains the 85 cam roller *s*⁵ in engagement with the cam *s*⁶. The mechanism *s*¹, *s*³, *s*⁵, *s*⁶, *s*⁷ is employed in bringing the pin *s*³ into and out of the engaging range of the hook *s*². The element *s*¹ of the coupler mechanism is adapted to position 90 the coupler pin element *s*³ to be engaged by the coupler hook element *s*² when the roller *s*⁵ turns upon the low or active part *s*⁶ of the cam *s*⁶ (Fig. 5). When the pin *s*³ is in engaging range of the hook *s*² the hook engages the pin when the hook is moved in a clockwise direction by its own weight. After the pin *s*³ and hook *s*² have been engaged the cam *s*⁶ depresses the hook lever *s*¹ (as in Fig. 3) and consequently lowers lever *r* to 100 turn the shaft 57² of the tripping mechanism of the printing cylinder 21 in a clockwise direction to lower the cam 58¹ of this second tripping mechanism out of the path of the roller *m* whereupon the hook 59 may 105 engage the tooth *e* as shown in Fig. 3 with the results that the second printing cylinder will be lowered to non-printing position as has been described in connection with the operation of the tripping mechanism pertaining to the printing cylinder 17 of the first printing couple, both tripping mechanisms being generally similar in function and construction, similar parts of these mechanisms being given similar characters 110 of reference.

The printing cylinder 17 of the first printing couple carries a cam *t* fixed upon its shaft 18, this cam having a high portion *t*¹ and a low portion *t*². When the cylinder 120 17 is in impression position the high part *t*¹ of the cam *t* is effective to keep the hook *s*² out of the position in which the pin *s*³ could engage this hook while the trailing portion *t*² of the cam permits the adjustment 125 or movement of the hook *s*² in position to be engaged by the pin *s*³ (see Figs. 3 and 5), the low part *t*² of the cam *t* permitting the hook to remain in position to be engaged by said pin, an engagement which occurs when 130

the roller s^5 passes over the cutaway or active portion s^8 of the cam s^6 (see Fig. 3). The parts t^1, t^3 of the cam t desirably perform their functions through the intermediate 5 action of mechanism which is inclusive of a cam lever t^4 pivoted at t^5 and carrying a cam roller t^6 engageable by parts t^1, t^3 of the cam t when the cylinder 17 is in impression position, the entire cam t being withdrawn 10 from operating relation to the roller t^6 when the cylinder 17 is in its lowered or non-printing position. When the cam roller t^6 passes over the cam portion t^3 the lever t^4 is lowered, by its own weight, against the stop 15 t^0 . A flexible rod t^8 constitutes a continuation of the lever t^4 and extends into the range of movement of the pin s^9 carried upon the hook lever s^1 . When the high part of the cam t is brought into engagement with 20 the cam roller t^6 it turns the lever t^4 in a clockwise direction to place the rod t^8 thereof in the position indicated by dotted lines in Fig. 2 in which position the pin s^9 is engaged by the lower end of the rod t^8 to hold 25 the hook lever s^1 in the position shown by dotted lines in Fig. 2 whereby the coupler pin s^3 cannot engage the hook s^2 during the time that the cylinder 17 is in impression position as shown in dotted lines in Fig. 2 30 and while the cam roller t^6 is passing through the position a, b of the cam groove d^1 . When the low part t^2 of the cam t underlies the roller t^6 or when the printing cylinder 17 is in its lower or non-printing position in 35 which the high part t^1 of the cam t cannot engage the cam roller t^6 the lever t^4 and its extension t^8 are in the position indicated by full lines in Fig. 2 in which the lower end of the rod t^8 is withdrawn from the range 40 of movement of the pin s^9 permitting the hook lever s^1 to rotate by its own weight in a clockwise direction and bears against the pin s^3 until the cam s^6 presents its active portion s^8 to the roller s^5 (see left hand 45 corner of Fig. 5), the roller s^5 being caused to follow the cam portion s^8 by the turning action of the spring s^7 upon the lever s^4 . When the low part t^2 of the cam t is beneath the cam roller t^6 and also during the entire 50 time the printing cylinder 17 is in non-printing or lowered position the cam t has no influence upon the positioning device which controls hook lever s^1 so that this hook lever is permitted to move in a clockwise 55 direction of its own weight and is therefore free to couple the tripping mechanism of the printing cylinder of the second printing couple with such cylinder. The high part t^1 of cam t is so disposed that it does not 60 come into effective relation with the roller t^6 until some time after the cylinder 17 has been raised into printing position; that is, the transmission of the movement of said cylinder 17 into printing position to the 65 lever s^1 is delayed until the tripping opera- tion of the second couple has been completed and said lever s^1 is allowed to perform its tripping function without interference, see Fig. 3. Thus when the cylinder 17 of the first printing couple is in its normal position, its 70 impression or printing position, it operates mechanism for preventing the coupler and the tripping mechanism of the printing cylinder of the second couple which is controlled by the coupler, from functioning 75 while the printing cylinder of the first couple is in printing operation. I desirably employ attendant controlled means for preventing the tripping mechanism of the printing cylinder 21 to come into operative 80 association with this cylinder. The attendant controlled means is desirably the lever structure t^4, t^8 itself, supplemented by an operating handle t^9 . When this attendant controlled means is to perform the function 85 for which it is provided the handle t^9 is moved in a clockwise direction until the lever t^4 engages the stop t^0 whereupon the rod t^8 is in the dotted position illustrated in 90 Fig. 2 to move the hook lever s^1 to the dotted position shown in this figure with the results hitherto specified. By means of this mechanism a sheet may be printed upon by the printing cylinder 21 of the second couple only, assuming that the printing cylinder 17 of the first couple has been tripped. If it is desired to have printing cylinder 17 95 of the first couple to print alone upon a sheet passing through the press, rod u , which is connected to the lower end of rod 100 t^8 and is provided with an operating handle u^1 at its upper end, is pulled upwardly to deflect the rod t^8 from the position shown by dotted lines in Fig. 2 to the position 105 shown in full lines whereby this rod t^8 is maintained out of the range of movement of the pin s^9 to allow the hook lever s^1 to turn in a clockwise direction due to its own weight to enable it to be engaged by the 110 pin s^3 . The rod u may be locked in the position shown in full lines in Fig. 2 by means of the hook u^2 pivoted upon the handle u^1 and engageable with the pin u^3 fixed upon the frame of the press. 115 When the cylinders 17 and 21 are to be tripped it is necessary, after the cylinder 17 is tripped, that sufficient time elapse before the cylinder 21 is tripped for the sheet last printed by cylinder 17 to pass from impression cylinder 11 and to be received 120 therefrom and to pass one and one-half times around the sheet transfer cylinder 16 and thence to pass to impression cylinder 26. The cylinder 17 may be tripped at the desired time by first pressing the key A at 125 or about the time that the parts are as shown in Fig. 3 and when the hook 59 of the cylinder lowering and elevating mechanism pertaining to the tripping mechanism of cylinder 17 is in its lower position, Fig. 3, 130

and at this time the grippers 59 of cylinder 11 are in the position shown in Fig. 3 just before which the arc $a\ b$ of the cam groove d^1 has been passing the roller i and during 5 which travel of the cam portion $a\ b$ by the roller i the depressed foot key A will be effective to engage the hook 59 with the tooth e to trip the cylinder 17 by the operations hitherto described. When the printing form 10 35 is in the position illustrated in full lines in Fig. 2 the cam s^6 is on the point of moving into position in which the cam roller s^5 will enter the cam portion s^8 to allow the pin s^3 to be positioned to permit the hook 15 s^2 to swing in position beneath it as will be seen in Fig. 5, the active portion t^1 of the cam t then being out of operative relation with the roller t^6 , which permits the rod t^8 to keep its position shown by full 20 lines in Fig. 2. The rod t^8 being in this position, the pin s^9 is free of its influence and the pin s^3 , now being over the hook s^2 , will push the hook lever s^1 downwardly, the pin s^3 itself being pushed downwardly by 25 the action of the cam s^6 upon the roller s^5 . As a consequence of this operation the cam arm 58 is lowered to bring the cam 58¹ out of range of the roller m whereupon the hook 59 on its return movement will drop into 30 engagement with the tooth e to cause the cylinder 21 of the second printing couple to be tripped to its lowered position as indicated in Fig. 3, but this dropping of the hook 59 to engage tooth e only occurs after 35 the cam d has made one complete revolution and the roller i is passing through the arc $a\ b$. By this time the cylinder 17 has made one revolution and has been raised to printing position but the high part t^1 of the cam 40 t has not at this time reached the roller 6 to move the rod t^8 to disengage the hook s^2 from the pin s^3 . It will be seen that the cam d of the first printing cylinder 17 has caused this cylinder to be automatically 45 raised to a printing position in the same revolution in which this cylinder was tripped. Should the key A be released at this time the hook 59 will assume its disengaged position so that the cylinder 17 50 will not be tripped on the ensuing revolution. When the cam roller t^6 is engaged by the active part t^1 of the cam t (which is when the cylinder 17 has been restored to the printing position shown by dotted lines 55 in Fig. 2, the corresponding raised position of the cam t being also indicated by dotted lines in this figure) and should the cam t be moved around as shown by the dot and dash lines, also shown in Fig. 2, by a further movement of the cylinder 17, the hook 60 lever s^1 is turned in a counter-clockwise direction against its own weight to break the couple s^2, s^3 , this result occurring when the cam roller s^5 is in the bottom of the active 65 part s^8 of the cam s^6 . In this operation the

spring r^2 turns the lever r and the cam arm 58 in a counter-clockwise direction to bring the cam 58¹ into engagement with the cam roller m to cause the disengagement of the hook 59 of the tripping mechanism having the coupler $s^2\ s^3$ from the tooth e , this action taking effect at the time the printing cylinder 21 is automatically restored to its printing or impression position during the same revolution in which it was tripped. 75

In order that the press may be adapted for offset printing, one of the printing cylinders, and preferably each of the printing cylinders, is provided with a form cylinder, there being form cylinder B for printing cylinder 17 and form cylinder B¹ for printing cylinder 21. The printing cylinder 17 is adapted to be brought into and out of printing relation with its complementary form cylinder B and the impression cylinder 11. 80 The printing cylinder 21 is adapted to be brought into and out of printing relation with its complementary form cylinder B¹ and the impression cylinder 26. As the press is shown equipped the printing cylinders 17 90 and 21 are each provided with a form plate B² while the cylinders B B¹ are shown as being unprovided with any form plates but the applicability of form plates to these cylinders B B¹ is illustrated by the representation of 95 form plates B³ by dotted lines. When the press is to be converted to an offset press the forms B² are replaced by the usual rubber sheets or offset bodies and the forms B³ are supplied to the cylinders B B¹. The form 100 cylinders B B¹ print up on such offset bodies that replace the forms B² and the printing upon these offset bodies is offset or transferred to the sheets upon the corresponding impression cylinders 11 and 26. When the 105 press is converted to an offset press the inking mechanism B⁴ will ink the form plates B³ and the moistening mechanism B⁵ will moisten such plates. The inking mechanism B⁶ that pertains to the printing cylinders 17 110 and 21 is withdrawn to the dotted positions shown in Fig. 3 when the press is used as an offset press.

Suitable intermeshing gearing is employed 115 to rotate the form cylinders B B¹ counter-clockwise, assuming that the printing cylinders 17 and 21 move clockwise. Other gearing is employed suitably to operate the inking mechanism B⁴ and the moistening mechanism B⁵ (if the press is used as an offset 120 press) or the inking mechanism B⁶ (if the press is used as a type letter press).

Referring now more particularly to Fig. 5, there is there shown mechanism constructed and functioning similarly to mechanism illustrated in remaining figures of the drawing. In this figure the printing cylinder 21 is partially illustrated and an additional printing cylinder C (a member of a third printing couple) is also illustrated. 130

This printing cylinder C is equipped with a tripping mechanism and a coupler similar to that which pertains to the printing cylinder 21, parts of the coupler and tripping mechanism pertaining to cylinder C which are similar to described parts of the coupler and tripping mechanism pertaining to cylinder 21 being given similar characters of reference. Other parts are employed in conjunction with the cylinder C which are similar to parts employed in conjunction with cylinder 21 and are also given similar characters of reference. Suitable intermeshing gearing may be employed between the cylinder C and the cam mechanism of the tripping mechanism belonging to this cylinder for turning the cams. Cylinder D is an impression cylinder having an association with cylinder C similar to the association of impression cylinder 26 with cylinder 21. The cylinder E has a relation to cylinder D similar to that of cylinder 16 with cylinder 26. There are two additional transfer cylinders F and G operating in conjunction with transfer cylinder E to present the wet side of a printed sheet to the cylinder C for a third printing operation on such wet side. While I have herein shown a two color and three color press arrangement by which the printing is all done on the same side of each sheet I do not wish to be limited to this adaptation of my invention. Suitable intermeshing gearing is employed for operating the additional cylinders C, D, E, F and G in proper relation to the balance of the press equipment.

The cylinder 21 is equipped with cam mechanism and other parts that are similar to cam mechanism and other parts illustrated in connection with the cylinder 17, and similar parts are given similar characters of reference.

The rod T^s governs the coupler that is employed to link the printing cylinder of the third or final couple with its tripping mechanism. This rod performs the functions of both rods t^s and u as its lower end may be swung toward and away from pins s³. The rod T^s is operable by a lever T⁴ pivoted at T⁵. Lever T⁴ is operated by hand lever H (operating through link H¹) when the rod T^s is to be withdrawn from the range of pin s³ to maintain the members of the coupler pertaining to the tripping mechanism of the third couple in cooperative relation. This rod T^s is moved toward pin s³ (when said coupler is to be rendered functionless) by the cam t of the second couple (Fig. 5) through the intermediation of the cam roller T⁶, lever T⁴, and the aforesaid link H¹. Lever T⁴ operates through its arm T⁷ that works upon collar H² fixed upon link H¹, the arm being yieldingly held against said collar by spring H³, so that the rod T^s can be moved, by manual

movement of the lever H to the right, to render said lever S' of the third tripping mechanism functionless independently of the cam t. It will be observed that ample breast room and head room for the passage of a press attendant intervenes between the third printing couple and the inking mechanism of the second printing couple, a clear passage way being afforded by the elevation or location of the mechanism H¹, T⁴, T^s outside of or overhead the space between said printing couple and the inking mechanism of the adjacent couple.

It will be understood that the cam t of the second printing couple is similarly positioned with respect to the cam t of the first printing couple in order that the couple pertaining to the tripping mechanism of the third or final printing couple may be properly timed. It has been seen that the cam t of the first printing couple and the mechanism it operates constitutes a positioning means to enable the functioning of the couple of the tripping mechanism of the second printing couple to cause the tripping of the printing cylinder of the second couple. The cam t of the second couple in turn constitutes a positioning means to enable the functioning of the coupler of the tripping mechanism of the third printing couple to cause the tripping of the printing cylinder of the third couple.

As illustrated, the sheet passing from the first printing couple to the second printing couple arrives at the second printing couple within the time limits (as heretofore described) of a cycle of the timing of coupling cam s⁶ and tripping cam d of the second couple and which cycle is equal in time to a corresponding printing cycle to enable the tripping mechanism of the second couple to trip its cylinder through hook 59 and tooth c of the tripping mechanism. Similarly, the sheet passing from the second printing couple to the third printing couple within the time limits of a cycle of the timing or coupling cam s⁶ and tripping cam d of the third couple and which cycle is equal in time to a corresponding printing cycle, to enable the tripping mechanism of the third couple to trip its cylinder through the hook 59 and tooth c of this tripping mechanism. If, for example, the second printing cylinder were omitted and the sheet traveled over the cylinders 11, 16, 26, G, F, and E to the last printing couple D, C, the sheet would not arrive at the last printing couple in the time of a printing cycle as heretofore described. The tripping mechanism and coupler and cam mechanism F T⁴ stationed at the second printing cylinder would therefore still be required to arrange for the arrival of the sheet at the last printing couple within the time limits of a cycle of the timing or coupling cam s⁶ and tripping cam d of the last

printing couple to enable the tripping mechanism of the last couple to trip its cylinder through the hook 59 and tooth *c* of this tripping mechanism, just the same as though 5 the second printing cylinder were present. From the foregoing it will be observed that I have produced a multi-couple, multi-revolution printing machine, the couples of which are adapted to print on the same side 10 of the sheet, in combination with two printing couples, the first couple having a cylinder normally in impression position but movable out of impression position, interrupting means (tripping mechanism) for 15 breaking the printing relation between the members of each couple normally inactive but adapted to act sequentially, when properly positioned, and controlling means for positioning said interrupting means in separate cycles of the machine. 20

While I have herein shown and particularly described the preferred embodiment of my invention I do not wish to be limited to the precise details of construction shown as 25 changes may readily be made without departing from the spirit of my invention, but having thus described my invention I claim as new and desire to secure by Letters Patent the following:—

30 1. A printing press including two cylinders; tripping mechanism for each of said cylinders; means for controlling the tripping mechanism of one of said cylinders; mechanism operated by the other cylinder, 35 while in impression position, for preventing said controlling means from functioning to position said tripping mechanism to trip; and timing means included in said last mentioned mechanism whereby the operative effect 40 of the movement of said other cylinder into impression position is delayed until after such movement.

2. A printing press including two cylinders; tripping mechanism for each of said 45 cylinders; a coupler for co-operatively relating one of said cylinders with its tripping mechanism; mechanism operated by the other cylinder while in impression position, for preventing said coupler and the tripping 50 mechanism it controls from functioning; and timing means included in said last mentioned mechanism whereby the operative effect of the movement of said other cylinder into impression position is delayed until 55 after such movement.

3. A printing press including two cylinders; tripping mechanism for each of said cylinders; a coupler for co-operatively relating one of said cylinders with its tripping 60 mechanism; mechanism operated by the other cylinder while in impression position, for preventing said coupler and the tripping mechanism it controls from functioning; and timing means included in said last mentioned 65 mechanism, said mechanism also including

an operative connection between said means and said other cylinder adapted to actuate said timing means and to move the same bodily in unison with said other cylinder whereby the operative effect of the movement of said other cylinder into impression position is delayed until after such movement. 70

4. A printing press including two cylinders; tripping mechanism for each of said cylinders; a coupler for co-operatively relating one of said cylinders with its tripping mechanism; mechanism operated by the other cylinder while in impression position, for preventing said coupler and the tripping 75 mechanism it controls from functioning; and a cam included in said last mentioned mechanism, said mechanism also including an operative connection between said cam and said other cylinder adapted to rotate said cam and to move the same bodily in unison with said other cylinder, the timing of said cam being such that the operative effect of the movement of said other cylinder into impression position is delayed until after such 80 movement. 85

5. A printing press including two cylinders; tripping mechanism for each of said cylinders; a coupler for co-operatively relating one of said cylinders with its tripping 90 mechanism; mechanism operated by the other cylinder while in impression position, for preventing said coupler and the tripping mechanism it controls from functioning; and a cam included in said last mentioned mechanism, said mechanism also including an operative connection between said cam and said other cylinder adapted to rotate said cam and to move the same bodily in unison with said other cylinder, the timing of said cam being such that the operative effect of the movement of said other cylinder into impression position is delayed until after such 95 movement. 100

6. A printing press including two cylinders; tripping mechanism for each of said cylinders; a coupler for co-operatively relating one of said cylinders with its tripping mechanism; mechanism operated by the other cylinder while in impression position for preventing said coupler and the tripping 105 mechanism it controls from functioning; and a cam included in said last mentioned mechanism, said mechanism also including an operative connection between said cam and said other cylinder adapted to rotate said cam and to move the same bodily in unison with said other cylinder, the movement of 110 said other cylinder out of impression position rendering said cam functionless. 115

7. A printing press including two cylinders; tripping mechanism for each of said cylinders; a coupler for co-operatively relat- 120

- from functioning and which mechanism is inclusive of a cam operated by this latter cylinder; and automatic mechanism for restoring to printing position the tripped cylinder having said coupler and operating in the same revolution in which this cylinder is tripped.
16. A printing press including two cylinders; tripping mechanism for each of said cylinders; a couple for coöperatively relating one of said cylinders with its tripping mechanism, the other cylinder being normally in impression position; mechanism operated by the latter cylinder, while in a printing cycle, for preventing said coupler from functioning and which mechanism is inclusive of a cam operated by this latter cylinder; and automatic mechanism for restoring to printing position the tripped cylinder having said coupler and operating in the same revolution in which this cylinder is tripped.
17. A printing press including two cylinders; tripping mechanism for each of said cylinders; a couple for coöperatively relating one of said cylinders with its tripping mechanism, the other cylinder being normally in impression position; mechanism operated by the latter cylinder, while in impression position, for preventing said coupler and the tripping mechanism it controls from functioning and which mechanism is inclusive of a cam operated by this latter cylinder, the coupler functioning when this latter cylinder is in non-printing position; and automatic mechanism for restoring to printing position the tripped cylinder having said coupler and operating in the same revolution in which this cylinder is tripped.
18. A printing press including two cylinders; tripping mechanism for each of said cylinders; a couple for coöperatively relating one of said cylinders with its tripping mechanism, the other cylinder being normally in impression position; mechanism operated by the latter cylinder, while in a printing cycle, for preventing said coupler from functioning and which mechanism is inclusive of a cam operated by this latter cylinder, the coupler functioning when this latter cylinder is in non-printing position; and automatic mechanism for restoring to printing position the tripped cylinder having said coupler and operating in the same revolution in which this cylinder is tripped.
19. A printing press including two cylinders; tripping mechanism for each of said cylinders; means for controlling the tripping mechanism of one of said cylinders; mechanism operated by the other cylinder, while in impression position, for preventing said controlling means from functioning to allow said tripping mechanism to trip; means included in said last mentioned means whereby the operative effect of the move-
- ment of said other cylinder into impression position is delayed until after such movement; and automatic mechanism for restoring to printing position said one cylinder after it is tripped and operating in the same revolution in which this cylinder is tripped.
20. A printing press including two cylinders; tripping mechanism for each of said cylinders; a coupler for coöperatively relating one of said cylinders with its tripping mechanism, mechanism operated by the other cylinder, while in impression position, for preventing said coupler and the tripping mechanism it controls from functioning; means included in said last mentioned mechanism whereby the operative effect of the movement of said other cylinder into impression position is delayed until after such movement; and automatic mechanism for restoring to printing position the tripped cylinder having said coupler and operating in the same revolution in which this cylinder is tripped.
21. A printing press including one single revolution cylinder; a second cylinder operating second in printing; tripping mechanism for each of said cylinders; and automatic means operating in each revolution of said single revolution cylinder whereby the tripping mechanism of the second cylinder is positioned in the printing cycle ahead of the printing cycle in which the tripping mechanism of the first cylinder is positioned.
22. A printing press including one single revolution cylinder; a second cylinder operating second in printing; tripping mechanism for each of said cylinders; and automatic means governed by the first cylinder in its printing operation whereby the tripping mechanism of the second cylinder is positioned in the printing cycle ahead of the printing cycle in which the tripping mechanism of the first cylinder is positioned.
23. A printing press including one single revolution cylinder; a second cylinder operating second in printing; tripping mechanism for each of said cylinders; automatic means operating in each revolution of said single revolution cylinder whereby the tripping mechanism of the second cylinder is positioned in the printing cycle ahead of the printing cycle in which the tripping mechanism of the first cylinder is positioned; and positioning means governing only this last tripping mechanism.
24. A printing press including one single revolution cylinder; a second cylinder operating second in printing; tripping mechanism for each of said cylinders; automatic means governed by the first cylinder in its printing operation whereby the tripping mechanism of the second cylinder is positioned in the printing cycle ahead of the printing cycle in which the tripping mech-

anism of the first cylinder is positioned; and positioning means governing only this last tripping mechanism.

25. A printing press including one single revolution cylinder; a second cylinder operating second in printing; tripping mechanism for each of said cylinders; automatic means operating in each revolution of said single revolution cylinder whereby the tripping mechanism of the second cylinder is positioned in the printing cycle ahead of the printing cycle in which the tripping mechanism of the first cylinder is positioned; and attendant controlled positioning means governing only this last tripping mechanism.

26. A printing press including one single revolution cylinder; a second cylinder operating second in printing; tripping mechanism for each of said cylinders; automatic means governed by the first cylinder in its printing operation whereby the tripping mechanism of the second cylinder is positioned in the printing cycle ahead of the printing cycle in which the tripping mechanism of the first cylinder is positioned; and attendant controlled means governing only this last tripping mechanism.

27. A printing press including one printing couple; a second printing couple operating second in printing, each of said couples having a cylinder, the cylinder of the second couple being a single revolution cylinder; tripping mechanism for each of said couples; automatic means governed by the first cylinder in its printing operation and operating in each revolution of said single revolution cylinder whereby the tripping mechanism of the second couple is positioned in the printing cycle ahead of the printing cycle before that in which the tripping mechanism of the first couple is positioned; and positioning means governing only this last tripping mechanism.

28. A printing press including one printing couple; a second printing couple operating second in printing, each of said couples having a cylinder, the cylinder of the second couple being a single revolution cylinder; tripping mechanism for each of said couples; automatic means operating in each revolution of said single revolution cylinder whereby the tripping mechanism of the second couple is positioned in the printing cycle ahead of the printing cycle before that in which the tripping mechanism of the first couple is positioned; and attendant controlled positioning means governing only this last tripping mechanism.

29. A printing press including one printing couple; a second printing couple operating second in printing, each of said couples having a cylinder, the cylinder of the second couple being a single revolution cylinder; tripping mechanism for each of said couples; automatic means governed by the first cyl-

inder in its printing operation and operating in each revolution of said single revolution cylinder whereby the tripping mechanism of the second couple is positioned in the printing cycle ahead of the printing cycle before that in which the tripping mechanism of the first couple is positioned; and attendant controlled means governing only this last tripping mechanism.

30. A printing press including a form cylinder; a printing cylinder; an impression cylinder; mechanism for establishing printing relation and breaking the same between the printing cylinder and the other cylinders; a cylinder in another printing couple; tripping mechanism for this latter cylinder; a coupler for co-operatively relating said tripping mechanism with its cylinder; and mechanism operated by one of the other cylinders, while in impression position, to prevent said coupler and the tripping mechanism it controls from functioning.

31. A printing press including a form cylinder; a printing cylinder; an impression cylinder; mechanism for establishing printing relation between the printing cylinder and the other cylinders; a cylinder in another printing couple; tripping mechanism for this latter cylinder; a coupler for co-operatively relating said tripping mechanism with its cylinder; mechanism operated by one of the other cylinders, while in impression position, to prevent said coupler and the tripping mechanism it controls from functioning; and means included in said last mentioned mechanism whereby the operative effect of the movement of said other cylinders into impression position is delayed until after such movement.

32. A printing press including a form cylinder; a printing cylinder; an impression cylinder; mechanism for establishing printing relation and for breaking the same between the printing cylinder and the other cylinders; a cylinder in another printing couple; tripping mechanism for this latter cylinder; means for controlling said tripping mechanism; mechanism operated by one of said cylinders in said first mentioned group, while in printing relation with its complemental cylinders, for preventing said controlling means from functioning to position said tripping mechanism to trip; and timing means included in said last mentioned mechanism whereby the operative effect of the movement of said one cylinder into printing relation with its complemental cylinders is delayed until after such movement.

33. A printing press including a form cylinder; a printing cylinder; an impression cylinder; mechanism for establishing printing relation and breaking the same between the printing cylinder and the other cylinders; a cylinder in another printing couple;

- tripping mechanism for this latter cylinder; a coupler for coöperatively relating said tripping mechanism with its cylinder; automatic means whereby the tripping mechanism is positioned in the printing cycle ahead of the printing cycle in which this tripping mechanism may be tripped; and mechanism operated by one of the other cylinders, while in impression position, to prevent said coupler and the tripping mechanism it controls from functioning.
34. A printing press including, a form cylinder; a printing cylinder; an impression cylinder; mechanism for establishing printing relation between the printing cylinder and the other cylinders; tripping mechanism for one of said cylinders; a coupler for coöperatively relating the tripping mechanism with its cylinder; an additional cylinder; and mechanism operated by the additional cylinder, while in a printing cycle to prevent said coupler and the tripping mechanism it controls, from functioning.
35. A printing press including a form cylinder; a printing cylinder; an impression cylinder; tripping mechanism for one of said cylinders; a coupler for coöperatively relating the tripping mechanism with its cylinder; an additional cylinder; mechanism for moving this latter cylinder into and out of impression position; and means operated by said additional cylinder for preventing said coupler from functioning when this cylinder is in impression position.
36. A printing press including a form cylinder; a printing cylinder; an impression cylinder; tripping mechanism for one of said cylinders; means for controlling said tripping mechanism; an additional cylinder; mechanism for moving this cylinder into and out of impression position; a coupler for coöperatively relating the tripping mechanism with its cylinder; an additional cylinder; mechanism operated by this cylinder for preventing said coupler from functioning when said additional cylinder is in impression position; and timing means included in said last mentioned mechanism whereby the operative effect of the movement of said additional cylinder into impression position is delayed until after such movement.
37. A printing press including a form
- cylinder; a printing cylinder; an impression cylinder; tripping mechanism for one of said cylinders; means for controlling said tripping mechanism; an additional cylinder; mechanism for moving this cylinder into and out of impression position; mechanism operated by this latter cylinder while in impression position for preventing said controlling means from functioning to position said tripping mechanism to trip; and timing means included in said last mentioned mechanism whereby the operative effect of the movement of said additional cylinder into impression position is delayed until after such movement.
38. In a multi-couple press, the combination with adjacent printing couples; of an offset form cylinder for one couple and located between the couples; inking mechanism for said offset form cylinder and located between the couples; inking mechanism for one of the couples and located between the couples, a passageway intervening between said inking mechanism for one couple and the other couple for an attendant; interrupting means for breaking the printing relation between the members of said couples; and positioning mechanism intervening between one printing couple and the interrupting means of the next printing couple and so located as not to obstruct said passageway.
39. In a multi-couple press, the combination, with adjacent printing couples; of an offset form cylinder for one couple and located between the couples; inking mechanism for said offset form cylinder and located between the couples; inking mechanism for one of the couples and located between the couples, a passageway intervening between said inking mechanism for one couple and the other couple for an attendant; interrupting means for breaking the printing relation between the members of said couples; and positioning mechanism intervening between one printing couple and the interrupting means of the next printing couple and located over said passageway.

In witness whereof I hereunto subscribe my name this sixth day of March, A. D. 1917.

ROBERT MIEHLE.
